[57] CLAIM

The ornamental design for a lifting hook, as shown and described.

DESCRIPTION

FIG. 1 is a side elevation of a lifting hook of my design;
FIG. 2 is a left-hand end elevation thereof;
FIG. 3 is a right-hand end elevation thereof;
FIG. 4 is a top plan view thereof;
FIG. 5 is a bottom plan view thereof;
FIG. 6 is an elevation showing the opposite side of the lifting hook of FIG. 1; and,
FIG. 7 is a sectional plan view taken as indicated by the line 7—7 of FIG. 6.

FIG. 2**FIG. 1****FIG. 3****FIG. 4****FIG. 5****FIG. 6****FIG. 7**
